DESIGN FOR A KNITTED FABRIC

Max Weber, Brooklyn, N. Y.

Application January 11, 1940, Serial No. 89,388

Term of patent 3½ years

To all whom it may concern:

Be it known that I, Max Weber, a citizen of the United States, residing at Brooklyn, New York, in the county of Kings and State of New York, have invented a new, original, and ornamental Design for a Knitted Fabric, of which the following is a specification, reference being had to the accompanying drawing, forming part thereof.

The figure is a top plan view of a knitted fabric showing my new design.

The areas represented by the reference numeral A are rows of stitches comprising the knit fabric background and the areas represented by the reference numeral B are raised ribs formed of parallel loose yarns arranged transversely of the rows of stitches of the knitted background.

I claim:

The ornamental design for a knitted fabric, as shown and described.

MAX WEBER.
